(57) **CLAIM**

I claim the ornamental design for a beverage dispensing device, as shown.

DESCRIPTION

FIG. 1 is a top plan view of a beverage dispensing device showing my new design.

FIG. 2 is a bottom plan view thereof.

FIG. 3 is right side elevational view thereof, the left side being a mirror image of the right side.

FIG. 4 is a perspective view thereof from the front and right side.

FIG. 5 is a perspective view thereof from the front and left side.

FIG. 6 is front elevational view thereof; and,

FIG. 7 is rear elevational view thereof.
